United States Patent Office

Des. 187,178
Patented Feb. 9, 1960

187,178

HAT OR SIMILAR ARTICLE

Henry E. Knaust, St. Louis, Mo.

Application November 3, 1958, Serial No. 53,264

Term of patent 14 years

(CL. D3—13)

FIG. 1

The essential features of the design reside in the portions shown in solid lines on the drawing.

I claim:

The ornamental design for a hat or similar article, substantially as shown and described.
